EXTRACTION OF FATTY MATTER FROM GARBAGE AND OTHER FAT-CONTAINING MATERIALS.

1,372,479.

Specification of Letters Patent. **Patented Mar. 22, 1921.**

Application filed May 15, 1919. Serial No. 297,312.

To all whom it may concern:

Be it known that we, VLADIMIR BREDLIK, a citizen of the Republic of Czecho-Slovakia, residing in the city, county, and State of New York, and LOUIS C. WHITON, Jr., a citizen of the United States, residing in the city, county, and State of New York, have invented certain new and useful Improvements in the Extraction of Fatty Matter from Garbage and other Fat-Containing Materials, of which the following is a specification.

This invention relates to the extraction of grease, fats and oils from garbage, slaughter house refuse, and grease, oil or fat-containing materials; and comprises a process of extracting such fats and oils under varying pressure with a suitable solvent without subjecting the material under treatment to a heat sufficient to injure the fats and oils contained therein.

It is customary in present day practice to subject the refuse to a preliminary heating or drying before the extraction step, one of the primary objects being to render or rupture the cellular structure of the material. The temperature frequently reached in this preliminary heating is such that the grease and oils commence to decompose, the result being an extract dark in color, and inferior in quality.

An object of the present invention is to obtain an efficient extraction of the fats and oils previous to any heat treatment, and to thereby obtain a product of higher quality than that ordinarily produced.

Another object of the invention is to effect the extraction with as little handling of the garbage as possible.

The "green" garbage to which reference is made herein, and to which this invention is preferably applied, is a mass of garbage in the condition in which it is generally collected; that is without any heating or similar concentrating treatment except for the draining or pressing out of any excessive amount of water which may be found in it. The treatment of this still wet mass presents considerable difficulties, and especially difficulty in getting the solvent intimately distributed through the mass and into contact with the fat; which is mostly in the form of globules, each comprising a sort of closed cell or sack containing fat, which sacks must

be separated from one another and individually ruptured to insure full extraction by the solvent.

It is chiefly because of these difficulties with green garbage that the present day practice has generally included preliminary operations, such as heating or extended drying; which as compared with our process mean an added handling and expense and a detrimental effect on the quality of the grease extracted. The grease thus heated is partially carbonized and its fatty acids separated to some extent from the glycerin, so that its color is darkened and the acid content increased and it cannot be satisfactorily bleached. Our process, taking the garbage in the form of a wet mass as it generally occurs, saves preliminary expense; and, operating always at a comparatively low temperature, produces a light colored grease with low fatty acid content and of the best quality.

To accomplish the above object and such other objects as will appear in the following description we place the material from which grease is to be extracted in an extractor and create therein a negative pressure (say about 1 or 2 pounds absolute pressure, or 13 or 14 pounds below atmospheric), and then relieve this negative pressure rapidly; the material is then placed under a pressure of about 60 to 100 pounds above atmospheric maintained for some time depending on the nature of the material and this pressure is then relieved rapidly. These operations of subjecting the material first to negative and then to positive pressure with sudden relief, may be reversed without substantially changing the effect of cell rupture.

The material is then placed again under positive pressure (say of 20 to 30 pounds above atmospheric) and is caused to be practically submerged in a suitable fat-solvent such as gasoline, benzol, ether, etc. After remaining submerged for some time at this pressure the pressure is materially increased to about 60 to 100 pounds above atmospheric. The material in the extractor is allowed to remain for some time, depending upon its character, under the increased pressure, and preferably at a temperature below, or not much exceeding 50° C.

Our theory of the actions which take place within the mass is the following, but

whether this theory be inaccurate in whole or in part, we have found that the process gives a greater grease extraction than any other process with which we are familiar, 5 and secures its results without any heating of the material which might injuriously affect the quality of the fats obtained, so that such fats are of better quality and whiter in appearance than any which we have here- 10 tofore known to be extracted from such materials.

The action of the first vacuum operation is to rupture most of the cells by reason of their normal internal pressure of about 15 15 pounds absolute.

The succeeding high pressure then fills the material with compressed air and the sudden relief causes such air to separate the cells by its quick expansion and also prob- 20 ably acts to break cells which were not broken in the first step.

The pressure of 20 to 30 pounds then applied introduces compressed air into the several ruptured cells and into the inter- 25 stices of the material. Then when the solvent is introduced and the pressure increased to 60 or 100 pounds the solvent is forced also into the ruptured cells and interstices, where it dissolves the fats, and the air therein is 30 further compressed. And when this pressure is again relieved the compressed air in the cells and interstices assists in expelling the solvent and the dissolved fat therefrom, so that such solvent can all or nearly all be 35 withdrawn from the mass.

The pressures applied to the material are pressures of air or gas and may be produced by any suitable means.

Instead of the above described treatment 40 in connection with the solvent, we may proceed as follows. The solvent is introduced at atmospheric pressure, the pressure is then increased by 20 or 30 pounds to compress the air already in the broken cells and inter- 45 stices of the mass, and then a vacuum of say 2 pounds absolute is produced and causes the compressed air in the broken cells and interstices to expand with the same effect as before described; the important point being 50 the differential or comparative pressure which causes the air to expel the solvent with its dissolved grease and which is equally effective whether the absolute pressures be above or below atmospheric.

55 Depending chiefly on the nature of the material, the order in which the vacuum and pressure are applied before introducing the solvent may be varied without changing the principle involved. The following is a 60 specific example of the process.

The process may be illustrated in greater detail in connection with the accompanying drawing, which is a diagrammatic representation of an apparatus which we have found 65 to be suitable.

As will be apparent from the several legends on the drawing, the apparatus comprises, in addition to the extractor, an air-compressor and vacuum pump, a solvent pump, and a solvent reservoir. The vessels 70 into which the solvent is drained from the extractor are not shown on the drawing.

The green garbage or other material to be treated is placed in the extractor through the upper door 1 to about the level *a*, the 75 material resting on a perforated bottom 3. Starting with all valves closed, valves 4 and 5 are opened and the vacuum pump is operated, thus producing a vacuum in the extractor. After some time valve 16 is again opened and the 80 valve 16 is opened and the extractor brought again to atmospheric pressure. Valve 16 is then closed again and compressed air is pumped into the extractor. After a suitable time valve 16 is again opened and the 85 pressure relieved rapidly. Valve 16 is then closed. Valves 6 and 13 are opened and the air compressor is operated to raise the pressure in the extractor and in the solvent tank to a pressure greater than one atmosphere 90 and preferably to about 30 pounds. Valves 4 and 13 are then closed and valves 9 and 12 are opened to allow the solvent to flow by gravity from the solvent tank into the extractor until the material is entirely sub- 95 merged in the solvent.

During this first period of the extraction the grease on the surfaces of the lumps and particles which make up the material is dissolved, while the pores and interstices of 100 the particles are filled with compressed air which, at this stage, prevents the penetration of solvent into the garbage cells. Part of the cells are no doubt destroyed by the air pressure at this time, permitting penetration to a certain extent of the solvent into the tissue.

After the extractor is filled with solvent all valves are closed, valves 8 and 10 are opened and the solvent pump is operated 110 until the pressure in the extractor has been increased by several atmospheres and registers about 80 to 100 pounds. Or the same effect may be produced by closing all valves, then opening 4 and 5 and increasing the air 115 pressure upon the upper surface of the solvent. This increased pressure causes a further rupturing of the cells and forces the solvent into the inner recesses of the material and facilitates the action of the solvent 120 on the grease. At the same time the air which was retained in the pores of the garbage is further compressed.

The pressure of about 80 to 100 pounds in the extractor is maintained for some time depending upon the character of the material and the amount of grease therein. All valves are closed during this time except valve 7 which is opened to vent the solvent tank and produce atmospheric pressure therein 130

and then closed again. After a sufficient time has elapsed for the grease to be dissolved, the pressure in the extractor is relieved by opening valve 16. This reduction 5 of pressure allows the compressed air in the pores of the material to expand to thus further rupture the cell walls and expel the solvent with its dissolved grease. Valve 14 is then opened to drain off the solvent into a 10 suitable receiving vessel.

After all solvent has been drained off the valves 5 and 14 are closed, and the extractor is connected, by opening valve 15, to a suitable condenser, not shown in the drawing. 15 The valve 11 is then gradually opened to admit steam to the extractor. The effect of the steam passing through the garbage residue is to remove any remaining solvent. After all the solvent has been steamed out the 20 tankage is discharged through the door 2 and dried in the customary manner.

The chief advantage of our process is: the securing of a thorough penetration of the solvent throughout the garbage without a 25 preliminary heat treatment thereof sufficient to cause incipient decomposition of the fats and oils.

The vessels for extraction and for drying may be built according to any one of a number of usual or suitable designs for such purposes, and may be in either a vertical or a horizontal position and steam jacketed to regulate the temperature. Where the extractor is steam jacketed it is not necessary 35 to pass steam through the garbage to remove the residue of solvent. The introduction of steam into the jacket will drive off the residual solvent and also the moisture if it be desired to dry the garbage in the extractor.

40 Various modifications may be made in our process as above described, with such changes for instance in specific pressures as may be necessary to accomplish the desired extraction, without departing from the scope of 45 our invention.

What we claim is—

1. The process of extracting the fatty matter from garbage or other grease or oil-containing material, which comprises first 50 breaking the cells by variations of gaseous pressure thereon, and then subjecting the material to the action of the fat-solvent and then reducing the external pressure in comparison with the internal pressure to cause the 55 expulsion of the dissolved grease from the small pores and cells and separating the solvent with its dissolved grease from the residue.

60 2. The process of extracting the fatty matter from garbage or other grease or oil-containing material, which comprises subjecting said material at substantially atmospheric temperature to a comparatively high gaseous pressure and then, while under such 65 high pressure, to the action of a fat-

solvent, and then relieving the pressure and separating the solvent with its dissolved grease from the solid residue.

3. The process of extracting the fatty matter from garbage and other grease or oil-containing material, which comprises subjecting the mass of said material to be treated at substantially atmospheric temperature to a fat-solvent under a high gaseous pressure sufficient to force the solvent into a large proportion 75 of the cells and interstices of the material, maintaining the pressure for a time long enough to allow the fatty matter to be dissolved, and then relieving the pressure and separating the solvent with its dissolved 80 fatty matter from the solid residue.

4. The process of extracting the fatty matter from garbage and other grease or oil-containing material, which comprises subjecting the mass of said material to be treated 85 to a high gaseous pressure and to the action of a fat-solvent while keeping the temperature below a point at which appreciable decomposition of the fatty matter would occur, and then relieving the pressure and separating 90 the solvent with its dissolved grease from the solid residue.

5. The process of extracting the fatty matter from garbage and other grease or oil-containing material, which comprises subjecting the garbage or other refuse to a high gaseous pressure at substantially atmospheric pressure causing the material to become submerged in a fat-solvent while maintaining said pressure, then materially increasing 95 the pressure on said garbage and solvent to force the solvent into the inner cells and interstices of the garbage, and then relieving the pressure and separating the solvent with fatty matter dissolved therein 100 from the garbage residue.

6. The process of extracting the fatty matter from garbage and other grease or oil-containing material, which comprises subjecting the mass under treatment to variations of gaseous pressure in the absence of a solvent, then to a fat-solvent under a high pressure sufficient to force the solvent into a large proportion of the cells and interstices of the materials, maintaining the pressure 11 for a time long enough to allow the fatty matter to be dissolved, and then relieving the pressure and separating the solvent with its dissolved fatty matter from the solid residue.

7. The process of extracting the fatty matter from garbage and other grease or oil-containing material, which comprises subjecting said material successively to a high and low gaseous pressure followed in each 12 case by a sudden return of the pressure to atmospheric pressure, then subjecting said material to a high pressure and to the action of a fat-solvent while keeping the temperature below a point at which appreciable 13

decomposition of the fatty matter would occur, and then relieving the pressure and separating the solvent with its dissolved grease from the solid residue.

5 8. In the process of extracting the fatty matter from garbage and other grease or oil containing material by means of a solvent, the preliminary steps which comprise subjecting the mass of material under treatment 10 in the absence of the solvent to alternately higher or lower gaseous pressures.

9. In the process of extracting the fatty matter from garbage and other grease or oil containing material by means of a solvent, 15 the preliminary steps which comprise subjecting the mass of material under treatment in the absence of a solvent to gaseous pressures which are alternately above and below the normal pressure each being followed by 20 a return of pressure to normal suddenly so as to break the cell structure by the resulting differences between the internal and external pressures on the cells.

10. The process of extracting the fatty 25 matter from garbage, slaughter house refuse and like material, which comprises first subjecting the mass of garbage or other refuse under treatment to a high gaseous pressure in the absence of a solvent, causing the material to become submerged in a fat-solvent 30 while maintaining said pressure, then materially increasing the pressure on said garbage and solvent to force the solvent into the inner cells and interstices of the garbage, 35 and then relieving the pressure and separating the solvent with fatty matter dissolved therein from the garbage residue, the process being carried out at a temperature below that at which the fatty matter begins 40 to decompose.

11. The process of extracting grease from 45 garbage which comprises subjecting the garbage to an air-pressure of several atmospheres, submerging the garbage in a fat-solvent while maintaining said pressure,

then increasing the pressure on the mixture of solvent and garbage by several more atmospheres and maintaining the latter pressure for a suitable time, then relieving the pressure and removing the solvent with its dissolved grease from the garbage residue. 50

12. The process of extracting grease from garbage which comprises subjecting the garbage to an air-pressure of several atmospheres, 55 submerging the garbage in a fat-solvent while maintaining said pressure, then increasing the pressure on the mixture of solvent and garbage by several more atmospheres and maintaining the latter pressure for a suitable time, then relieving the pressure and removing the solvent with its dissolved grease from the garbage residue, and finally subjecting the garbage residue to a current of steam to remove the remaining portion of solvent and grease and effect 60 a rendering of said garbage. 65

13. The process of extracting grease from garbage which comprises maintaining the garbage under a gaseous pressure of about thirty pounds while causing the garbage to 70 become permeated with a fat-solvent, then increasing the pressure to about eighty to one hundred pounds to force the solvent into the inner cells and recesses of the garbage, and then relieving the pressure and draining off the solvent with its dissolved grease, 75 the process being carried out at a temperature below about 50° C.

14. The process of extracting grease from garbage which comprises subjecting a mass 80 of the same in green condition to alternately higher and lower gaseous pressures in the absence of a solvent to break the cells thereof and then subjecting the mass to the action of a solvent and separating the solvent 85 with its dissolved grease from the residue.

In witness whereof, we have hereunto signed our names.

VLADIMIR BREDLIK.
LOUIS C. WHITON, JR.
